AND GEORGE R. BEARDSELL, OF NASHUA, NEW HAMPSHIRE.

LEATHER-FITTING MACHINE.

1,404,399.

Specification of Letters Patent. Patented Jan. 24, 1922.

Application filed February 10, 1921. Serial No. 443,821.

To all whom it may concern:

Be it known that I, EARLE B. LYONS, a citizen of the United States, residing at Nashua, in the county of Hillsboro and 5 State of New Hampshire, have invented new and useful Improvements in Leather-Fitting Machines, of which the following is a specification.

The type of machine to which this invention relates is one for performing the operation known technically in the art as fitting leather; that is, of compressing leather pieces having extended area to a substantially uniform or increased degree of firmness and density through pressure applied by means of a roll. This operation is performed mostly on leather having substantial thickness, wherein stiffness is an important consideration, such as that used for 10 soles, inner soles, counter stiffeners for shoes (commonly known as counters) toe caps, etc. Different parts of the skin or side of leather vary in firmness and closeness of texture, and unless they are brought to a substantially uniform condition in all parts, the soles, counters and other articles cut from leather are liable to be stretched and the leather are liable to be stretched and stresses applied in the subsequent operations 15 of trimming, channeling, skiving, etc.

The machines used for the purpose stated by which the best result and greatest homogeneity of the product are secured are those in which a rapidly reciprocating roll 20 of relatively short length is brought to bear upon the leather piece supported by a bed beneath the roll. Severe pressure must be applied through and by means of such roll in order to accomplish satisfactory results, because light pressure will not have any permanent effect in compressing the leather. And this pressure must be frequently relaxed and reapplied to allow different parts 25 of the leather piece to be placed in position to be operated on.

To effect great enough compression of the soft areas of leather pieces, which areas may be relatively small and of irregular outline, requires that the roll should be comparatively short and that it should be applied to limited areas of the leather at any one time; and the fulfillment of these requirements 30 compels the piece undergoing treatment to be shifted from time to time until all of its area has been rolled. Such shifting of the

leather can be accomplished in the desired manner only when the pressure of the roll has been relaxed.

Heretofore such machines of the sort just described as have gone into commercial use 40 have depended entirely upon the muscular effort of the operator to develop the necessary pressure between the roll and the work. Even with lever and toggle mechanisms having the greatest possible mechanical advantage, in proportion to the necessary range of separation between the work-support and the roll and to the range of movement possible to be allowed to the treadle on which the operator exerts force, the muscular effort 45 required is severe; and the laborious character of the work is intensified by the fact that the frequent relaxations of pressure necessary for shifting the work-piece have required this effort to be constantly relaxed 50 and reapplied. Practically the only way in which the operator can do this work is by standing on one foot and stepping with his other foot upon the treadle, raising himself and applying his whole weight to the treadle 55 when the need for extreme pressure occurs. Then the jar of the roll in passing over the edge of the work-piece, which always occurs when the outer parts of a piece are being worked upon, is communicated through the 60 mechanism to the operator and increases the fatiguing effect of his labor. In short, then, operators of these machines have been required to perform the hardest and most 65 exhausting sort of labor and at the same time 65 to manipulate the work-pieces and exercise skill and judgment in so presenting them to the action of the roll that they may be treated over their whole areas as quickly as possible and with the least possible labor. 70 These conditions have resulted, in many cases, in causing more or less serious bodily injury to operators and have made it difficult for the producer of fitted leather to secure operators who are willing and able to 75 work with these machines.

Many efforts have been made in the past to provide an automatic or semi-automatic means for applying pressure of the sort required in these machines, for the benefit both 80 of the welfare of the work people and of the manufacturer for whose product there is needed the quality of the rolling action herein described, but all such efforts have 85 been abortive. My object has been to accom- 90

plish the result which has heretofore been unsuccessfully attempted, that is, to equip leather fitting machines of the type here described with labor-saving pressure-applying mechanism.

This object has been accomplished by the means which I will now describe in connection with the following specification and the drawings forming a part thereof disclosing the preferred embodiment of the present invention.

Referring to the drawings:—

Figure 1 is an elevation of the machine in which my invention is embodied as viewed 15 from the side opposite to that on which the operator takes his position.

Figure 2 is a sectional view on an enlarged scale taken on line 2—2 of Figure 1 and showing in elevation the parts at the 20 right of said line.

Figure 3 is a section on line 3—3 of Figure 2.

The same reference characters indicate the same parts wherever they occur in all 25 the figures.

The structure designated by the numeral 5 represents a frame which is massive enough to support the moving parts and sustain the stresses applied by and through 30 such parts without sensible distortion. 6 is a table on which is mounted a work-supporting bed upon which the leather pieces to be compressed or fitted by rolling action are placed one at a time. That part of the 35 table which supports the bed is made of a springy board or plank which is secured at its ends to the rigid frame and is adapted to be sprung upwardly in its middle part to press the work-piece against the roll. 40 Other boards or planks may be arranged in front and in rear of the one which supports the bed so as to furnish a table of as great an area as may be required, having regard to the size of the pieces of leather which 45 may be operated upon.

The roll which acts upon the leather is shown at 8. Its trunnions are mounted rotatively in the carriage 9 which travels on a guideway 10 supported from the overhanging frame. It carries trundle rolls 11 which bear on a rigid track or runway 12 through which the reaction thrust of the roll is borne. A pitman 13 is connected by a wrist-pin 14 to the carriage and by a 55 crank-pin 15 to the disk 16 on a shaft 17 driven by a pulley 18 and belt 19 from a conveniently located counter shaft. This pulley is driven at a high enough speed to give a rapid reciprocation to the roll in a 60 path included between the extremities of the bed. The roll may have any diameter which is not so small as to concentrate the pressure upon an area so narrow as to injure the leather, and on the other hand is 65 not so large as to distribute the pressure too

widely to obtain great enough unit intensity of pressure. In its length (in the direction of its axis) the roll is short enough to apply concentrated pressure to zones of much less width than the dimensions of the pieces 70 operated on.

On the bottom member of the frame there is mounted a block 20, which rests on a rubber pad 21, or equivalent yielding and resilient bottom, in order to absorb the shocks 75 which occur when the roll passes over the edge of the work-piece and to quench the vibrations resulting from this cause.

A fulcrum member 22 rises from the block 20 and supports a lever 23. This fulcrum member is in the nature of a plate or blade set edgewise having a blunt, rounded upper edge which enters a groove in the enlarged rounded end of the lever in a manner similar to a knife edge bearing. In the 85 upper part of the lever, a short distance to one side of a vertical plane through the fulcrum member, is a notch which receives the lower end of a toggle link 24, the latter being a plate tapered to a blunt knife edge at 90 both of two opposite edges. The upper edge enters a notch 25 in the under side of a secondary lever 26 which is connected with the lever 23 by a link 27. In the upper side of the lever 26 and laterally offset from the 95 vertical plane through the bearing center of the toggle link and secondary lever is a notch which receives the lower edge of a lifter bar 28, which bar is adapted to apply force through adjusting screws 29 and blocks 30 100 to the bed 7, either directly or through the spring beam on which the bed is mounted. The levers 23 and 26, with the link 24 and bar 28, form a double toggle linkage in which all of the fulcrum points are brought 105 more or less nearly into line when the outer arm of lever 23 is depressed, the secondary lever 26 then being moved in unison with lever 23 by the connecting link 27.

Upright guides 301 embrace trunnions 23^a 110 and 26^a on the fulcrum ends of the levers 23 and 26, respectively, maintaining these parts of said levers in vertical alinement while permitting the trunnions 26^a to rise and descend.

Figure 1 shows the machine in the relaxed position when the lever arms are raised and the toggle linkage is broken, the bed being then separated from the roll by a space wide enough to permit insertion of 120 leather pieces having the thickness of sole leather. A spring arm 31, fixed at one end to the frame and coupled at its other end through a link 32 with the link 23, normally returns the lever mechanism to the position 125 shown when intermission of the pressure impulse permits. This effect is assisted by the spring of the flexible beam on which the bed is mounted. This lever and toggle mechanism transforms pressure applied on 130

the long arm of lever 23 into a greatly multiplied thrusting force of the bed toward the roll. The intensity of the pressure so exerted upon a piece of leather and likewise the location of the path in which the bed is moved may be modified by adjustment of the screws 29.

Power mechanism is provided for applying force upon the lever 23 under control of the operator, and this mechanism consists of a belt pulley 33 loosely mounted on a shaft 34, a clutch for coupling said pulley to said shaft, a second shaft 35 carrying a gear wheel 36, which is driven by a pinion 37 fixed on the shaft 34, and an arm 38 clutched frictionally on shaft 35 and carrying a roll 39 arranged to bear on arm 23. The clutch which I have provided for connecting pulley 33 to shaft 34 at the will of the operator is of a well known friction type and is partly shown in Figure 2. The friction producing elements are controlled by levers 40 which are adapted to be spread apart by a conical ended sleeve 41 sliding on the shaft 34 and movable endwise thereon by means of arms 42 fast to a rock-shaft 43 and having studs or rolls which enter an encircling groove 44 in said sleeve. When this sleeve is moved to the right, with respect to Figure 2, the clutch levers 40 are spread apart and the clutch is set; conversely, when the sleeve is moved in the opposite direction the clutch is released and the belt pulley is allowed to turn idly. I have not attempted to show the details of the clutch because said details are not a part of my invention and the particular clutch which I have adopted is obtainable in the open market and is well known. The belt which drives the pulley 33 is shown at 45 and is driven from a countershaft. (Not shown.)

Shifting of the clutch-operating sleeve is effected in one direction by a treadle 46 pivoted to brackets 47 on the bed frame and connected by a link 48 with an arm 49 keyed to rock-shaft 43; and in the opposite direction by a spring 50 attached at one end to said arm and at the other end to a lug 51 on the frame.

The friction clutch by which arm 38 is mounted on shaft 35, and through which force is applied to said arm, is shown in detail in Figure 3. It comprises a sleeve 52 keyed to the shaft, a hub 53 on arm 38 (which embraces part of said sleeve) and a block 54 of suitable friction causing material, such as hard wood, contained in a holder 55 which is secured by bolts 56 to lugs projecting from opposite sides of the hub 53. The sleeve 52 and hub 53 are preferably made of metal, as steel or cast iron, and the hub may be lined with any of the metals used for bearings, or it may be lined with wood or other friction causing material. Wood is preferred for the friction

block 54 and for the frictional lining of hub 53 (when such a lining is provided) because it combines the qualities of a large enough coefficient of friction with great resistance to the effects of wearing. Other friction- 70

causing materials may be used with good effect, however. The degree of friction is determined, according to need, by setting up or relaxing the bolts 56. A counterweight 57 is provided to raise the arm 38, or to assist 75 the spring arm 31 in doing so, when the power application is discontinued.

It is to be understood that the roll 8 is reciprocated constantly whether any leather is presented to the operating bed or not and that 80 pressure is applied upon the bed toward the roll when a piece of leather is in position to be rolled upon, and is relaxed when such piece is to be removed or shifted. When pressure is to be applied for this purpose, the 85 operator presses on the treadle 46, thereby coupling lever 33 to shaft 34, and the arm 38 is then caused to press on and depress the lever 23. When this lever is depressed as far as it will go, (this movement being pref- 90

erably limited by a stop 58) the friction clutch 53, 54 slips, but constantly maintains enough pressure to hold the toggle linkage in the displaced position to which it has thus been brought; thus causing the leather to be 95 forced against the roll with the desired degree of pressure. But the initial force is applied and maintained mechanically and the operator's exertion is limited to the effort needed to prevent the spring 50 from 100 returning the treadle and uncoupling the primary clutch, which effort is so slight as to be inappreciable and to have no fatiguing effect. Instead of the operator being required to apply his whole weight on the 105 treadle and be continually stepping up and down, he needs now only to make slight movements of his foot about the ankle joint, and may even sit down to his work. His whole attention may then be given to the 110 manipulation of the leather necessary for bringing all of its parts under the action of the roll. An equivalent treadle arranged to operate the primary clutch substantially in the manner herein described may be arranged for use by the operator when standing on the floor.

What I claim and desire to secure by Letters Patent is:

1. In a leather-rolling machine having a 120 work-supporting bed and a reciprocating roll, forming a leather rolling couple of which one of the members is movable toward and away from the other for exerting and relaxing pressure on the interposed work 125 piece, the improvement in mechanism for forcing that member of said couple which is so movable toward the other member, consisting of a power driver, a driven member connectible with said driver, operator-con- 130

- trolled means for connecting and disconnecting said driver and driven member, and a force-transmitting mechanism arranged to receive force application from said driven member and apply force to the movable member of said couple.
2. In a leather rolling machine having a work-supporting bed and a reciprocating roll, forming a leather rolling couple of which one of the members is movable toward and away from the other for exerting and relaxing pressure on the interposed work piece, the improvement in mechanism for forcing that member of said couple which is so movable toward the other member, consisting of a power driver, a driven member connectible with and disconnectible from said driver, under control of the operator, and a transmission mechanism arranged to receive motion and force from said driven member, and to transmit diminished motion with increased force to the movable member of said couple, said transmission mechanism including machine elements frictionally clutched together, one of which is adapted to slip relatively to the other when the predetermined limit of force transmission is reached.
3. In a leather rolling machine having a work-supporting bed and a reciprocating roll, forming a leather-rolling couple of which one of the members is movable toward and away from the other for exerting and relaxing pressure on the interposed work piece, the improvement in mechanism for forcing that member of said couple which is so movable toward the other member, consisting in the combination with a lever having a long arm arranged to receive force and a short arm arranged to deliver force with multiplied intensity to said movable member, of a power-actuated driver, and intermediate means between said driver and said long lever arm arranged to transmit force and motion from the former to the latter.
4. In a leather fitting machine including the combination of a work supporting bed, a reciprocatable roll arranged to travel over said bed and a pressure multiplying mechanical linkage constructed and arranged to apply pressure through the bed and roll to an interposed work-piece, the combination with said linkage of a power mechanism under the control of an operator adapted to exert force upon said linkage.
5. In a leather fitting machine as set forth in Claim 4, and in which the pressure multiplying linkage is provided with an arm adapted to receive pressure applications, the characteristics of said power mechanism as

comprising a driven shaft and a pressure applying arm frictionally mounted upon said shaft and arranged to be pressed against the first-named arm.

6. In a leather fitting machine as set forth in Claim 4, the characteristics of said power mechanism as comprising a shaft, a pulley loose with respect to said shaft, a primary clutch operable by the operator for connecting and disconnecting said pulley with and from said shaft, and means frictionally driven by said shaft for applying force to said pressure multiplying linkage.

7. In a leather fitting machine including a reciprocating roll and a work-supporting bed forming a leather-rolling couple, one member of which is movable toward and away from the other for applying pressure to a work-piece interposed between them and for relaxing said pressure, respectively, and a lever and toggle mechanism arranged to exert pressure upon the movable member of said couple toward the other member and having a load receiving arm, power mechanism for loading said arm comprising a shaft, an arm frictionally clutched upon said shaft and arranged to be operated by rotation of the latter into position for applying force to the load-receiving arm, a driver for said shaft, and an operator-controlled primary clutch for effecting alternate connection and disconnection of said driver with and from said shaft respectively.

8. In a leather rolling machine having a reciprocatively traveling roller, a bed for supporting work in position to be pressed upon by said roller and mechanism for applying pressure through said bed against a work-piece interposed between the bed and roller, the combination with said mechanism of a power mechanism for exerting and maintaining intermittent pressure upon the aforesaid mechanism which consists of a rotatable shaft, an arm mounted upon said shaft and having a frictionally gripping medium by which it is secured to the shaft with provision for slipping thereon when it encounters a sufficiently non-yielding resistance, said arm being arranged to bear against the load-receiving part of said pressure-applying mechanism, a driver loosely mounted with respect to said shaft, a primary clutch adapted to connect said driver with said shaft, and operator-controlled means for connecting and disconnecting said clutch.

In testimony whereof I have affixed my signature.

EARLE B. LYONS.

Certificate of Correction.

It is hereby certified that in Letters Patent No. 1,404,399, granted January 24, 1922, upon the application of Earle B. Lyons, of Nashua, New Hampshire, for an improvement in "Leather-Fitting Machines," errors appear in the printed specification requiring correction as follows: Page 1, strike out line 27 and after the word "and," line 28, insert the words *squeezed out of shape by the pressures and*; and that the said Letters Patent should be read with these corrections therein that the same may conform to the record of the case in the Patent Office.

Signed and sealed this 7th day of March, A. D., 1922.

[SEAL.]

WM. A. KINNAN,

Acting Commissioner of Patents.
